(57) CLAIM

The ornamental design for an “ornamented shoe,” as shown and described.

DESCRIPTION

FIG. 1 is a perspective view of the top, front and right side of the ornamented shoe;

FIG. 2 is a right side elevation view thereof;

FIG. 3 is a front view of the ornamented shoe;

FIG. 4 is a left side elevation view thereof;

FIG. 5 is a rear view of the ornamented shoe;

FIG. 6 is a top view looking downwardly at the shoe from above;

FIG. 7 is a bottom view of the ornamented shoe; and,

FIG. 8 is a perspective view of the ornamented shoe showing the removal of the side element.

The broken-lines of FIGS. 1 through 8 depict shoelaces, a product logo and the tread on the bottom of the shoe. These broken line features are depicted for illustrative purposes only, and form no part of the claimed design.
